Duro Metal Products Company, Chicago, Ill.,
a corporation of Illinois**

Application December 3, 1936, Serial No. 66,285

Term of patent 14 years

To all whom it may concern:

Be it known that I, Theron L. Hedgpeth, a citizen of the United States, residing at Oak Park, in the county of Cook and State of Illinois, have invented a new, original, and ornamental Design for a Band Saw Head, of which the following is a specification, reference being had to the accompanying drawing forming part thereof.

Fig. 1 is a side elevational view of a band saw head embodying the design;

Fig. 2 is a bottom plan view;
Fig. 3 is an elevational view showing the rear side of Fig. 1;

Fig. 4 is a front elevational view;
Fig. 5 is a rear elevational view of the band saw head, seen from the left of Fig. 1.

I claim:

The ornamental design for a band saw head, as shown.

THERON L. HEDGPETH.
